Application February 27, 1945, Serial No. 580,045

4 Claims. (Cl. 179—171)

1

My invention relates to an electrical amplifying system and method suitable for the amplification of direct currents and relatively low frequency alternating currents. More specifically, my invention relates to an electrical system and method of coupling a discharge device to an amplifier so as to reduce or entirely eliminate the effect of cathode drift of the discharge device on the output of the amplifier. The system may be regarded broadly as a current amplifier and voltage regulator.

In the past, discharge devices, such as electrometer tubes of various types, have been used for amplifying very minute electrical currents. A troublesome effect, commonly known as cathode drift, was generally encountered, especially in highly sensitive discharge devices, manifesting itself in a slow erratic fluctuation of output current or voltage and being detected readily when the direct current voltage applied to the input for amplification is maintained at a constant value or zero. It is generally believed that cathode drift results from changes in filament current or from changes in the active filament coating or minute changes in the cathode temperature; in any event, cathode drift manifests itself in changes of electron emission currents emitted by the cathode. Cathode drift is especially important and troublesome when it appears in or near the input stage of a multi-stage amplifier because although minute, its effect is magnified substantially by the fact that that very high current amplification is obtained, for example an amplification of the order of 250,000, in certain electrometer tubes for amplifying very small currents. Obviously, if additional amplifying stages are added, the effect of cathode drift is still further amplified thus introducing considerable error in the output signal.

On object of my invention is to eliminate or substantially reduce the effect of cathode drift in an electrical amplifier.

A more specific object of my invention is to provide an electrical system for coupling a pair of space charge devices in a manner so that cathode drift in one of the devices will not be amplified and translated through the other device, whereas the input signal will be so amplified and translated.

A further object of my invention is to provide an improved multi-stage amplifier adapted for the faithful amplification of direct current, or alternating current at low frequencies, particularly those below 1,000 cycles per second.

A further and more specific object of my in-

2

vention is to provide a voltage regulating system in a high-sensitivity, multi-stage amplifier, that is useful to eliminate or substantially reduce the effect of cathode drift originating, for example, in a highly sensitive electrometer tube used in the first stage of such amplifier.

A still further and more specific object of my invention is to provide a voltage regulating system providing highly amplified corrective effects to compensate for cathode drift.

Another object of my invention is to provide a novel method of translating amplified currents so as to render them devoid of distortion caused by cathode drift.

Other objects and advantages will become more apparent from a study of the following specification taken together with the drawing wherein a schematic diagram shows an illustrative direct current electrical amplifying system embodying 20 the teachings of my invention.

Referring more particularly to the drawing, T_1 denotes an electric discharge device or tube and is illustrated as a high vacuum, space charge tetrode tube of high sensitivity, comprising an input or control electrode or grid 1, an anode or plate 2, a space charge grid or electrode 3, and a thermionic cathode 4. Tube T_1 is, preferably, one having a high input resistance and a very low grid current so as to give maximum benefits when used to measure or translate very small currents or voltages. An example of such tube is the G. E. "Pliotron" tube type FP-54, having an input resistance of 10^{16} ohms, a current amplification of 250,000 when used with an input resistor of 10^{12} ohms, and a voltage amplification factor of unity. Such tube is particularly adapted for the amplification or measurement of currents of less than 10^{-9} amperes. A voltage source, indicated by battery 5, provides the plate voltage, the polarity of its terminals being indicated by symbols + and -. The anode 2 and cathode 4 of tube T_1 are energized by the plate voltage source through a series connected plate resistor 6. The inner grid, that is, the space charge grid 3, is connected to the positive terminal 7 of the plate voltage source through resistor 8 and series resistor 9 so that the space charge grid 3 will be maintained at a positive potential with respect to cathode 4. A voltage source or grid bias battery 10 is connected between the negative terminal 11 of the plate voltage source and the cathode 4 to give a negative bias to the input or control electrode 1, for example, in the neighborhood of -2 to -4 volts with respect to cathode 4. Suitable operation is obtained if anode 2 is main-

tained at +6 volts with respect to cathode 4, space charge grid 3 at +4 volts with respect to cathode 4, the battery 5 having a potential of 90 volts. The input signal is applied between control grid 1 and the negative terminal 11 of the plate voltage source 5.

An electric discharge device or tube T_2 is provided for amplifying and regulating the output current of tube T_1 , and is illustrated as a double triode having a common cathode 12, two anodes 13 and 14, and two control electrodes or grids 15 and 16, associated with anodes 13 and 14, respectively. Tube T_2 preferably has a high amplification factor, and tubes such as, for example, the RCA type 6SC7 or 6SL7 are suitable. As illustrated, the triode at the left of tube T_2 comprises the amplifier section, and the triode at the right, the regulating section of the double triode tube. The grid 15 of the amplifier section is connected to the plate 2 of the tetrode tube T_1 and the common cathode 12 is connected to the negative terminal 11 of the plate supply through a cathode resistor 17. The anode 13 of the amplifier section is connected to the positive terminal of the plate supply through a series load resistor 18. It is the voltage drop across resistor 18 that is to be regulated or controlled since such voltage drop is fed into the output or subsequent stages of the amplifier. In the control or regulating section of the double triode tube T_2 , control grid 16 is connected to the space charge grid 3 of tetrode tube T_1 through the resistor 8, and the anode 14 is connected directly to the positive terminal 7 of the plate voltage supply. Terminals 11 and 19 constitute the output terminals of tube T_2 .

The above-described amplifying system is useful to amplify and transmit a signal fed to the control grid 1 of the space charge tetrode T_1 . If it is assumed that the incoming signal voltage is such as to cause the control grid 1 to become more positive with respect to the cathode 4, such increase in positive signal voltage increases the conductivity of tube T_1 and results in an increase in the voltage drop across plate resistor 6. Anode 2 thus becomes more negative than under static conditions with respect to the potential of terminal 11 as does also the control grid 15 of the amplifier section of tube T_2 .

The increase in positive signal voltage will cause a greater number of the electrons emitted from the cathode 4 to be accelerated through the inner or space charge grid 3 resulting in a decrease in the space charge grid current, and in turn resulting in a decrease in the voltage drop across the resistors 8 and 9 connected in series therewith. This decrease in voltage drop results in an increase in the positive potential of the space charge grid 3 as well as an increase in positive potential of the control grid 16 of the regulator section of double triode tube T_2 connected therewith.

This increase in positive potential of control grid 16 results in an increase in plate current in the regulator section of tube T_2 and an increase in voltage drop through the cathode resistor 17. Thus the potential of cathode 12 is made to increase, that is, to tend to follow the voltage impressed on control grid 16. The function of resistor 8 is to increase the positive bias on grid 16 so as to make it substantially equal to the bias on grid 15.

Since the voltage applied to the grid 15 of the amplifier section of the double triode T_2 is lowered as the result of the increase in signal input voltage to control grid 1 and since the potential of com-

mon cathode 12 of tube T_2 is increased, the two changes produce a gross change in grid-to-cathode potential of the amplifier section that causes the plate current flowing through the load resistor 18 to decrease, resulting in a decrease in the voltage drop in such load resistor. This change in voltage drop of the load resistor 18 constituting the output may be fed into subsequent stages of the amplifier, representing the amplified signal of the input signal impressed on the control grid 1 of tube T_1 .

The amplifying system described also acts as a regulator to control variations of cathode emission current, generally referred to as cathode drift. If it is assumed that for some reason, other than changes in the input current or voltage, the cathode emission of tube T_1 is increased, the plate current and space charge grid current of T_1 will both increase as a result of such increase in cathode emission. The increase in space charge grid current and plate current causes a decrease in the positive bias applied to both of the grids 15 and 16 of double triode tube T_2 . This decrease in positive potential on the grid 16 of the regulating half of tube T_2 causes a decrease in the current flowing through cathode resistor 17, resulting in a lowering of the cathode potential. The values of resistors 6, 8 and 9 are so chosen that for a given change in cathode emission current emitted by cathode 4 the change in voltage drop through resistor 6 will be equal to the change in voltage drop in resistor 9 causing an equal change of potential on the cathode 12 and the grid 15. Since the potential of both the cathode 12 and the grid 15 of the amplifier section of tube T_2 are changed in the same direction and by the same amount, there will be no net change in the relative potential therebetween. The plate current in the amplifying section of tube T_2 therefore remains constant for a steady signal input. More particularly, the plate current flowing through load resistor 18 will be independent of variations in cathode emission current of tetrode tube T_1 occurring otherwise than by changes in the input signal.

An outstanding advantage is obtained in the circuit illustrated by virtue of the fact that there is no metallic connection between space charge grid 3 and cathode 12, either directly or through resistors, the space charge grid 3 being connected solely to grid 16. By such connection solely to grid 16, changes in space charge grid current of tube T_1 are greatly amplified by the regulator section of tube T_2 thereby giving an amplified current flow and relatively high voltage drop across cathode resistor 17 thereby magnifying the voltage follow-up effect of cathode 12 relative to grid 16. If, on the other hand, space charge grid 3 were connected to cathode 12, either directly or through resistors, the space charge grid circuit would have to furnish the entire current flow through the cathode resistors to cause the necessary voltage drop to make cathode 12 change in potential in accordance with changes in space charge grid current, hence comparatively small voltage changes of cathode 12 will take place since there is no magnification of the space charge grid current changes.

To summarize the amplifying and regulating action of the circuit described, it may be stated that a change in input voltage of tube T_1 in one direction causes the grid and cathode of the control or regulator section of tube T_2 to change in the same direction but causes the grid of the amplifier section of tube T_2 to change in an op-

posite direction, thereby causing a net change in the relative potential of the grid and cathode in the amplifier section, hence in the value of current flow through the load resistor; on the other hand, with constant input voltage, a variation in a particular direction of the cathode emission of the tube T_1 causes the grid and cathode of not only the control or regulator section, but of the amplifier section as well, of tube T_2 to move in the same direction, thereby causing no net change in the relative potential of the grid and cathode in the amplifier section, hence causing no change in current flow through the load resistor. In other words, voltages of like polarity are applied to the second discharge device in such manner as to prevent translation therethrough of the effects of cathode drift of the first discharge device and the voltages of opposite polarity are applied to the second discharge device so as to convert said voltages into a fluctuating output voltage.

Thus it will be seen that I have provided an amplifying system suitable for amplifying direct currents or alternating currents, particularly those under 1,000 cycles per second, that is highly useful to amplify very small currents, for example, currents under 10^{-9} amperes; that I have incorporated in such amplifying system a circuit for coupling a space discharge device to a second space discharge device comprising a further amplifying stage and arranged so that changes in cathode emission current in the first space discharge device will not be amplified or translated through the second space discharge device or through subsequent stages of the amplifying system. I have thus provided a highly sensitive amplifier that incorporates features tending to make the output signal a true amplified replica of the incoming or input signal, resulting in high precision measurement or translation of minute currents. Furthermore, I have provided a novel method of translating an amplified signal devoid of distortions caused by cathode drift.

The above-described amplifying system should be regarded merely as illustrative and not limiting insofar as the present invention is concerned, and the invention should be restricted only insofar as set forth in the following claims.

What is claimed is:

1. An electrical amplifier comprising, in combination, a discharge device including a control electrode having an input signal voltage impressed thereon, and a pair of electrodes whose voltages change in opposite directions for a given uni-directional change in input signal voltage and change in the same direction for a given uni-directional change in cathode emission current resulting from causes other than that produced by a change in signal input, circuit means including two triodes having grids connected, respectively, to said pair of electrodes and having interconnected cathodes, resistance means for making said triode grids vary in voltage the same amount and in the same direction for said given uni-directional change of cathode emission current of said first-mentioned discharge device, resistance means in series with one of said triodes to make its cathode follow the potential of its grid and to make the grid and cathode of the other triode ineffective to translate said changes of cathode emission current occurring in said first discharge device, and an output circuit controlled solely by fluctuations in anode potential of said last-mentioned triode.

2. In a multi-stage amplifier adapted for amplification of alternating or direct current, an input stage comprising a space discharge device that has a cathode, space charge electrode, control electrode and an output electrode, an input circuit for said stage comprising said cathode and control electrode, an output circuit for said stage comprising said space charge electrode and said output electrode, circuit means including two triodes having grids connected, respectively, to said output electrode and said space charge electrode and having interconnected cathodes, resistance means for making said triode grids vary in voltage the same amount and in the same direction for a given uni-directional change of cathode emission current of said first-mentioned discharge device resulting from causes other than that produced by a change in signal input, resistance means in series with one of said triodes to make its cathode follow the potential of its grid and to make the grid and cathode of the other triode ineffective to translate said change of cathode emission current occurring in said first discharge device and an output circuit controlled solely by fluctuations in anode potential of said last-mentioned triode.

3. In a multi-stage amplifier adapted for amplification of alternating or direct current, an input stage comprising a space discharge device that has a cathode, space charge electrode, control electrode and an output electrode, an input circuit for said stage comprising said cathode and control electrode, an output circuit for said stage comprising said space charge electrode and said output electrode, circuit means including a double triode, each section of which has a grid, said grids connected, respectively, to said output electrode and said space charge electrode and having a common cathode disconnected from said space charge electrode, resistance means for making said triode grids vary in voltage the same amount and in the same direction for a given uni-directional change of cathode emission current of said first-mentioned discharge device resulting from causes other than that produced by a change in signal input, resistance means in series with one of said triodes to make said common cathode follow the potential of its grid and to make the triode including said common cathode and said grid connected to said output electrode ineffective to translate changes of cathode emission current occurring in said first discharge device, and an output circuit including said last-mentioned triode and controlled solely by anode potential changes thereof.

4. A direct current amplifier comprising, in combination, a discharge tube including a plate, cathode, control electrode and space charge electrode, an input circuit including said control electrode and cathode and an output circuit including said plate and space charge electrode, a source of direct current plate potential, a resistor connected between said plate and the positive terminal of said source, and a second resistor connected between said space charge electrode and said positive terminal of said source, said resistors being of such values that their voltage drop changes for given uni-directional changes in cathode emission current are substantially equal; discharge means including a pair of triodes, the grids of which are connected to said plate and space charge electrode, respectively, and equipotential cathodes connected to the negative terminal of said plate potential source through a third resistor, the anode of one of said triodes be-

ing connected to the positive terminal of said plate potential source through a load resistor, and an output circuit connected to said last-mentioned triode anode and controlled solely by changes in voltage drop across said load resistor thereby translating an amplified signal devoid of cathode drift effects originating in said first-mentioned discharge tube.
